UNITED STATES PATENT OFFICE.

CLARENCE L. JOHNSTON, OF OAKLAND, CALIFORNIA, ASSIGNOR TO MARCHANT CALCULATING MACHINE COMPANY, OF OAKLAND, CALIFORNIA, A CORPORATION OF CALIFORNIA.

CALCULATING MACHINE.

Application filed June 23, 1920. Serial No. 391,136.

To all whom it may concern:

Be it known that I, CLARENCE L. JOHNSTON, a citizen of the United States, and a resident of Oakland, Alameda County, State of California, have invented certain new and useful Improvements in Calculating Machines, of which the following is a specification.

The invention relates to calculating machines in which the figure discs of the registering mechanism are arranged on a carriage, which is disposed in parallel displaceable relation to the actuating mechanism, for the purpose of making the direct action of the units of the actuating mechanism on figure discs of different denomination possible. For this purpose the carriage is movable longitudinally in a step by step motion and the present invention relates to means for moving the carriage in a step by step motion in either direction.

An object of the invention is to provide a carriage moving mechanism which is positive and practically noiseless in operation and simple in construction.

The invention possesses other advantageous features, some of which, with the foregoing, will be set forth at length in the following description, where I shall outline in full that form of the invention which I have selected for illustration in the drawings accompanying and forming part of the present specification. In said drawings, I have shown one form of the invention, but it is to be understood that I do not limit myself to such form since the invention, as set forth in the claims, may be embodied in a plurality of forms.

Referring to said drawings:

Figure 1 is an elevation of the carriage moving device of my invention in its environment.

Figure 2 is an elevation of the device and the carriage base on a larger scale, with the front plate of the device removed to show its construction.

Figure 3 is a side elevation of the device. The calculating machine shown in the drawings, and which is one type of machine to which my invention is applicable, comprises a frame having side walls 2 between which the actuating mechanism is mounted and a base 3, projecting forward from the side walls and on which the carriage 4 is mounted in longitudinal displaceable rela-

tion, so that the figure wheels 5 of the registering mechanism may be moved in cooperative relation with different units of the actuating or counting mechanism. The carriage is movable in a step by step movement, the length of each step being equal to the spacing of corresponding parts of the figure discs, so that the figure discs are moved at each step to bring the discs of the next denomination into cooperative relation with the respective actuating units.

Secured to the carriage 4, and projecting therefrom, at the base, is a serrated bar 6, having a series of regularly spaced depressions in its upper surface, the spacing of the depressions being equivalent to the length of the step movement of the carriage. The depressions are preferably rectangular and contiguous, so that they form a series of rectangular serrations 7. Secured to the front of the base of the machine, usually at the center, is a housing 8, which is disposed above the toothed bar 6. Arranged within the housing are two oppositely disposed guide blocks 9-12, the blocks being pivoted on pins 13 secured in the housing. The blocks are spaced apart at their adjacent pivoted ends and are normally held in a horizontal position by the springs 14 connecting the blocks with the housing. Disposed in the pivoted blocks are slides 15-16 which are guided on the pivot pins 13 and which are provided with rounded lower ends adapted to enter the depressions in the bar 6. The slides are alined with depressions in the toothed bar, so that when a slide is projected it engages in a depression in the bar.

Pivots engaging the slides 15-16 are levers 18-19 pivoted in the respective blocks and provided on their ends with keys 21-22. The keys are normally held raised by springs 23, interposed between the lever and the housing. The springs 23 are weaker than the springs 14, so that when a key is depressed it operates to first move the slide into a depression in the toothed bar before the guide block is rocked on its pivot. When the slide has seated in the depression, further movement of the key causes the guide block to rock on its pivot, causing the slide to move the carriage. For example, depression of key 22 moves slide 16 into engagement with the rack, and then rocks the slide about the pivot of the block 110

12, moving the carriage one step to the right. When the key is released, the slide moves out of the depression and slides back into the block, which returns to its normal 5 position with the slide in position to be moved into engagement with the next depression. Similarly, depression of the key 21 causes the carriage to be moved one step to the left. When the carriage has been 10 moved a distance of one step, motion of the rocking block is halted and with the key depressed the slide is jammed in the depression in the rack bar, locking said bar against movement in either direction. The 15 carriage is thus positively moved in a step by step movement and overthrowing of the carriage is prevented. The key levers 18 and 19 are disposed so that the keys lie closely adjacent each other, and the front 20 plate of the housing is provided with slots through which the levers pass.

Means are also provided for accurately centering the carriage in displaced position and for preventing accidental movement of 25 the carriage during the time that the slide is out of engagement with the toothed bar.

Arranged in the rear wall of the housing, immediately over the toothed bar, is a spring pressed detent engaging the 30 toothed bar, preferably comprising a ball 27 pressed downward by a spring 28. The ball seats in a depression 7, and as the carriage is moved, the ball is raised and then springs into the next depression, properly 35 positioning the carriage.

The springs 23 for raising the keys may be dispensed with, when desired, and the springs 14 relied on to return the slides 15-16 and the keys to normal position.

40 The springs 14 return the blocks to normal position and, in the movement of the block to such position, the slide is forced upward by the inclined side of the depression in the serrated bar.

45 I claim:

1. In a calculating machine, a frame, a carriage movable on said frame, a toothed bar on said carriage and a slide pivotally mounted on said frame adapted to be moved 50 into contact with said bar and to be moved about its pivot to move said carriage.

2. In a calculating machine, a frame, a carriage movable on said frame, a toothed bar on said carriage, a slide adapted to be moved into engagement with said bar, a pivot member in which said slide is movable and means for moving said slide into engagement with the bar and moving said member about its pivot to move said carriage. 60

3. In a calculating machine, a frame, a carriage movable on said frame, a toothed bar on said carriage, a block pivoted to said frame, a slide in said block and a key adapted to first move the slide into engagement with the bar and then rotate said block on its pivot, whereby the carriage is moved. 65

4. In a calculating machine, a frame, a carriage movable on said frame, a toothed bar on said carriage, a pair of blocks pivoted to said frame, a slide in each block adapted to be moved into engagement with the bar, a key associated with each slide and springs for normally holding the keys in elevated position. 70

5. In a calculating machine, a frame, a carriage movable on said frame, a toothed bar on said carriage, a block pivoted to said frame, a spring holding said block in position, a slide in said block, a key engaging 80 said slide and adapted upon depression to move the slide into engagement with the bar and then rock the block on its pivot whereby the carriage is moved a definite distance. 85

6. In a calculating machine, a frame, a carriage movable on said frame, a toothed bar secured to said carriage, a block pivoted to said frame, a spring holding the block in position, a slide in said block engaging the block pivot, and a key lever fulcrumed in said block and pivotally engaging the slide, depression of the key lever serving to move the slide into engagement with the bar and then move the block on 90 its pivot. 95

In testimony whereof, I have hereunto set my hand at San Francisco, California, this 18th day of June 1920.

CLARENCE L. JOHNSTON.

In presence of—
W. W. HEALEY.
